CUP FOR REFRIGERATED COMMODITIES

Adam Ziska, Wauwatosa, Wis., assignor to
Samuel M. Kaufman, Milwaukee, Wis.

Application May 31, 1946, Serial No. 673,697

4 Claims. (Cl. 229—5.5)

1

This invention relates to improvements in cups for a refrigerated commodity.

Heretofore, numerous attempts have been made to design a satisfactory coin-controlled vending machine for a commodity such as icecream which requires refrigeration. In these devices, as heretofore proposed, it has been customary to support the filled cups in stacked relationship so that the bottommost cup may fall by gravity into the discharge chute in response to operation of the coin-controlled mechanism. However, due to the fact that the compartment within which the stacked cups are located must be maintained at a temperature below freezing, and due to the fact that a certain amount of moisture is necessarily contained in the air surrounding the cups, it has been found that condensed moisture will often cause freezing of the lower end or bottom rim of one cup to the cover of the cup therebelow. When this occurs, the bottommost cup will be restrained against falling by gravity, and the machine will fail to deliver merchandise.

It is a general object of the present invention to obviate the above mentioned objectionable feature by providing an improved cup and method, suitable for use in connection with vending machines, the cup being so constructed as to permit the use of a series of adjacent cups in a refrigerated chamber while materially limiting the amount of contact between the juxtaposed parts to prevent one cup from objectionably adhering to the cup thereadjacent.

A further object of the invention is to provide an improved cup as above described which is so constructed as to permit the vertical stacking of cups in the machine while materially limiting the amount of contact between the bottom of one cup and the top of the cup therebelow.

A more specific object of the invention is to accomplish the above purpose by means of one or more projections from or protuberances in the bottom of the cup which project below the lowermost edge portion of the bottom rim, said protuberances preferably being embossed.

A still further object of the invention is to provide a construction as above described which makes it possible to employ standard cup manufacturing procedures and machinery with the addition of embossing mechanism.

A further, more specific object is to provide in one form of the invention, a cup-bottom having a single central projection furnishing the sole contact with the cover of the cup therebelow, the projection extending a predetermined distance below the lowermost edge of the bottom rim.

2

Thus, said rim is maintained in a sufficiently elevated position to eliminate the possibility of adhesion.

With the above and other objects in view, the invention consists of the improved cups for a refrigerated commodity, and all its parts and combinations, as set forth in the claims, and all equivalents thereof.

In the accompanying drawing, illustrating two embodiments of preferred forms of the invention, in which the same reference numerals designate the same parts in all of the views:

Fig. 1 is a fragmentary sectional view through a guiding tube of a vending machine showing several icecream cups supported therein, parts of the cups being broken away and shown in vertical section;

Fig. 2 is a bottom view of one of the cups alone;

Fig. 3 is an elevational view illustrating several superimposed cups and incorporating a modified form of the invention, parts being broken away and shown in vertical section; and

Fig. 4 is a sectional view through one of the cups taken approximately on the line 4—4 of Fig. 3.

Referring more particularly to the drawing, the invention is particularly adapted for use in connection with cardboard cups of the "Dixie Cup" type. These cups are commonly used in the vending of individual servings of icecream. The invention may, however, be applied to cups of other types and shapes, to cups formed of materials other than cardboard, and to cups used for any purpose wherein they must be stored in contacting relationship in a freezing compartment.

The cup illustrated comprises a tapered side wall portion 8 which is circular in cross-section. During manufacture, the upper portion of the side wall may be rolled to form an internal annular shoulder 9 and the extreme upper edge is beaded as at 10. The usual flat cardboard cover 11 is adapted to be pressed into position to seat on the annular shoulder 9. The lower edge of the cup is preferably folded upwardly as at 12 to form a bottom rim with an upwardly opening circular recess for receiving the downwardly flanged circular edge 13 of a cardboard bottom 14. The construction just described is more or less standard and may be varied without affecting the novel features of the present invention.

As a part of the improved method, before the bottom members 14 are inserted in assembled position during manufacture, they are suitably fabricated to provide a projection which will ex-

tend downwardly beyond the lower edge 21 of the bottom rim. Preferably, the bottoms 14 are embossed, through the use of any suitable die, to provide a depending projection or protuberance 15 which is substantially an inverted cone in shape. In the preferred form of the invention, only one such projection is utilized and it is centrally located as is clear from Fig. 2.

It is, of course, possible to use any selected number of projections such as the three projections 16 illustrated in Figs. 3 and 4.

The projections may be formed differently or be of different shape than is illustrated, but the inverted conical shape is desirable as it permits a relatively deep embossing to be made without rupturing the cardboard, and also provides for a minimum of contacting area at 17 and 18.

The single central protuberance is, of course, preferred because it provides for a minimum of contact between superimposed cups. When this arrangement is utilized, it is contemplated that the cups be supported for discharge in the vending machine in a vertical guiding tube 19 which is of such size as to provide a small clearance at 20 between the edge of the bead 10 and the inner surface of the wall of the tube 19.

It is preferred to have the clearance about $\frac{1}{2}$ of an inch so that there is room for the cups to move freely downwardly by gravity without permitting too much tilting on the single protuberance. With this arrangement the cups may tilt sidewise only a short distance before a part of the rim 10 contacts a portion of the wall of the discharge tube 19. This contact will take place before any portion of the lower edge 21 of the bottom rim can contact the cover 11 of the cup below. Thus, by employing a suitable guiding tube 19 the single supporting projection will furnish ample support for the cup above and the contacting area at 17 will be so small that any adhesion due to freezing of condensed moisture will be insufficient to prevent the bottommost cup from gravitating to a point of discharge during the vending operation.

In the form of the invention illustrated in Figs. 3 and 4, the three depending projections 16 will furnish suitable support without permitting tilting and, therefore, the relationship between the size of the cups and the vending machine tube 19 is unimportant in this species of the invention. It has been found that the three projections or protuberances 16 will produce insufficient contacting area at 18 to interfere with the gravitating movement of the bottommost cup even though there is a certain amount of adhesion due to the freezing of condensed moisture.

Various changes and modifications of the structure may be made without departing from the spirit of the invention, and all of such changes are contemplated as may come within the scope of the claims.

What I claim is:

1. A stack of like cups for a refrigerated com-

modity each comprising a hollow body portion of fibrous material having a cover and having a bottom and having a bottom rim projecting below said bottom, said bottom having at least one projection depending therefrom with the bottom of the projection lower than the lower edge of the bottom rim and engaging the cover of the cup therebelow to minimize the possibility of frost adhesion between cups.

2. A cup for a refrigerated commodity comprising a downwardly tapered side wall of fibrous material which is circular in cross-section and which has a top rim, a bottom disc of fibrous material for closing the bottom of said side wall, said side wall having a bottom rim portion projecting below said bottom disc and of a size to fit loosely within the top rim of a like cup, a removable cover of fibrous material, and means for supporting said cover in depressed position within said top rim, said bottom disc having a projection which projects downwardly a greater distance than the bottom rim to support the latter in a position spaced above the cover of a like cup positioned therebelow when a plurality of cups is stacked.

3. A stack of like cups for a refrigerated commodity each comprising a hollow body of fibrous material having a cover and which is circular in cross-section and which has a bottom rim, there being a flat bottom portion depressed within said rim, and at least one projection depending from said flat bottom portion with the bottom of the projection lower than the lower edge of said bottom rim and engaging the cover of the cup therebelow to minimize the possibility of frost adhesion between cups.

4. A stack of like cups for a refrigerated commodity each comprising a hollow body portion of fibrous material having a cover and having a bottom and having a bottom rim projecting below said bottom, said bottom having at least one protuberance embossed therein with the bottom of the protuberance lower than the lower edge of the bottom rim and engaging the cover of the cup therebelow to minimize the possibility of frost adhesion between cups.
